WRAPPING MACHINE

Robert Roland Brightwell, Philadelphia, Pa., assignor to Stephano Brothers, Philadelphia, Pa., a corporation of Pennsylvania

Application September 5, 1941, Serial No. 409,629

5 Claims.

(Cl. 93—6)

This invention relates to an improved wrapping machine and particularly to a wrapping machine having a device for slitting one or more edges of the wrapper while it is being wrapped around the article so as to facilitate the opening or removal of the wrapper.

Various articles, such as cigarette packages, are wrapped in sheet material made of regenerated cellulose or some plastic material such as Cellophane, "Glassine" or the like. It is frequently difficult to remove the wrapper from the package because the smooth unbroken edge of such wrapping material offers resistance to tearing. The removal of the wrapper can be greatly facilitated by forming small slits or notches in one or more of the exposed edges thereof since the material may be readily fractured and the seal of the package broken.

It is an object of the present invention to provide improved apparatus for forming slits or notches in one or more of the exposed edges of the wrapper while it is being wrapped around the article or package.

A further object is the provision of improved apparatus of the above character which can be incorporated in a wrapping machine and can be synchronized therewith so as to automatically form the slits in the wrappers at the proper time.

Another object is the provision of an improved wrapping machine having a device for slitting wrappers incorporated therein which is of relatively simple construction and which will operate for a long period of time with comparative freedom from wear.

In the accompanying drawings

Fig. 1 is a sectional view through a wrapping machine incorporating a device for nicking wrappers embodying my invention;

Fig. 2 is a top plan view of a portion of the lower folding chute and the device for slitting the wrappers associated therewith;

Fig. 3 is a sectional view in the direction of the arrows on the line 3—3 of Fig. 2;

Fig. 4 is a perspective view of the upper portion of a cigarette package showing the projecting flaps of a wrapper having slits formed therein by means of my improved apparatus; and

Fig. 5 is a view of a package with a wrapper wrapped around the side and bottom thereof and projecting beyond the top.

My device for slitting wrappers may be used in connection with many different types of wrapping machines. However, I have found that it can be conveniently incorporated in the type

shown in my Patent No. 2,144,448, granted on January 17, 1939, and in the accompanying drawings I have illustrated the device in connection with such a machine.

5 The wrapping machine shown is particularly adapted to wrap cigarette packages in Cellophane or similar transparent sheet material. However, it may also be used for wrapping other packages and articles in sheet material. The pertinent 10 portions of the illustrated machine comprise the channel-shaped guide 5 through which the packages 6 are fed into the machine and the channel-shaped guide 7 communicating with one side of the guide 5 at right angles thereto and through 15 which the packages are fed by means of the reciprocating plunger 8 which is caused to reciprocate by the arm 9 pivotally connected at its upper end by means of a slotted connection to the plunger and pivotally mounted at an intermediate point 10 on the frame of the machine. The arm 9 is pivoted at its lower end 11 by means of a slotted connection to the arm 12 which, in turn, is pivoted to the machine at its central portion 14 and pivotally connected at its 20 lower end by means of a slotted connection 15 to a slide 16 carrying a follower 17 which engages a cam wheel 18.

The cam wheel 18 is mounted on shaft 19 which is driven by means of a sprocket chain 20 connected to the main drive shaft 21 of the machine. The main drive shaft 21 is in turn driven by means of a sprocket chain 22 connected to some suitable driving mechanism such as a prime mover or a shaft of the packaging machine which 25 packages the cigarettes. Plunger 8 is normally held in advance position by means of a spring 23 connected between the upper end of arm 9 and pin 24 fixed to the frame of the machine, and the cam 18, follower 17, and connecting 30 arms serve to retract the plunger.

The cigarette packages 6 are thus caused to advance through the guideway 7 by means of the plunger 8 until they reach the end thereof where they are fed downwardly by means of plungers 35 25 through the vertical folding chute 26. The plungers 25 are supported on cross arms 27 extending between a pair of sprocket chains 28, which are driven by sprockets 29 mounted upon shaft 30, which is slidably journaled in brackets 40 supported on the frame of the machine. The sprockets 29 are mounted at the lower end of the path of movement of the sprocket chains and at their upper end the sprocket chains are also supported by sprockets (not shown). The 45 shaft 30 supporting the sprockets 29 is con-

nected by means of sprocket chain 31 to shaft 32 which, in turn, is connected by meshing pinions 33 and 34 to shaft 35. Shaft 35, in turn, is connected by sprocket chain 36 to the main drive shaft 21 and, through the connections just described, it will be seen that shaft 30 and sprocket chains 28 are operated from the main drive shaft.

As the cigarette packages 6 enter the vertical folding chute 26, the lower ends thereof engage a wrapper blank 37, cut to the proper size. When the package is pressed into the folding chute, the wrapper will be forced up around the sides of the package and in the usual manner the wrapper is folded around the sides of the package. As shown, the folding chute is provided with ducts 38 for supplying an adhesive or solvent to the wrapper as it is folded around the package, and with heaters 39 for drying the adhesive or solvent. When the package 6 reaches the lower end of folding chute 26, the wrapper is folded completely around the bottom and four sides of the package and projects from the top thereof as shown in Fig. 5.

The package is then fed by reciprocating plunger 40 through the horizontal folding chute 41 which serves to fold the projecting ends of the wrapper over the top of the package. In order to cause the reciprocation of plunger 40, I pivotally connect the end thereof to arm 42 pivoted at an intermediate point 43 to the frame of the machine, and provided at the lower end thereof with a follower 44 which engages with cam 45 on the end of shaft 19. The plunger 40 is normally held in retracted position by means of spring 46, connected between the frame and the lower end of arm 42. The cam 45 causes the arm 42 to pivot, and plunger 40 to advance against the resistance of the spring.

As the cigarette package enters the folding chute 41, the first operation is the formation of the tucks 47 at opposite ends of the top of the package, by means of the fixed tucking plate 48 formed at the beginning of the folding chute 41, and the slideable tucking plate 49 projecting forwardly from the top of plunger 40. The slideable tucking plate 49 is connected to the top of plunger 40 by means of a slotted connection 50 which permits the tucking plate to assume the advance position shown in the drawings, or to be retracted so that the forward edge thereof does not project beyond the front face of the plunger. The tucking plate is normally held in advance position by means of spring 52, connected between pins 53 and 54.

After the tucks 47 have thus been formed in the wrapping material at the top of the package, the package is advanced through the horizontal folding chute with the flaps 55 and 56 projecting upwardly through the slots 57 and 58 on the two sides of top plate 59. The wrapper blank is so formed and positioned with respect to the package that one flap 55 is preferably shorter than the other flap 56. The shorter flap is first folded down against the package by means of diagonal slot 60, and thereafter the longer flap 56 is folded down over the shorter flap and over the top of the package by means of oppositely disposed diagonal slot 61. As in the vertical folding chute, a suitable adhesive or solvent for the wrapper may be applied thereto through duct 62, and the solvent or adhesive may be dried by means of heater 63. The fully wrapped packages are then discharged from the end of horizontal folding chute 41.

The wrapping machine mechanism just described forms part of a wrapping machine of the

type shown in my Patent No. 2,144,448, to which my improved device for forming slits or notches in the wrapper may be applied. I have described and shown sufficient portions of the machine to illustrate the manner in which the device may be applied to the machine. However, the machine just described does not constitute my present invention, and it should be understood that my device may be used in connection with other types of wrapping machines.

In carrying out my invention I have found that slits may be conveniently formed in the edges of one or both of the flaps 55 and 56 at the top of the package while the package is being fed through the horizontal folding chute 41. The mechanism which I employ for this purpose in the illustrated embodiment of my invention consists of a pair of knife blades 64 and 65 disposed above the folding chute 41 on opposite sides thereof adjacent the central portion of the slots 57 and 58. The knife blades are secured to the ends of arms 66 and 67 which are pivotally mounted at the points 68 and 69 at their opposite ends to a bracket 70, attached to the folding chute. The arms 66 and 67 may oscillate towards and away from each other causing the knife blades 64 and 65 to traverse the space above the slots 57 and 58. In this manner when the flaps 55 and 56 project upwardly through the slots 57 and 58, the knife blades cut the edges thereof so as to form slits or notches 71 therein. The knife blades are so positioned as to engage the flaps near the upper edge thereof as the slits preferably extend to the edges. Since the flap 56 is somewhat longer than the flap 55, blade 65 is positioned above blade 64.

I have found that it is desirable to provide a backing or support for the flaps while they are being cut in this fashion, and for this purpose I provide a block 72 having a central slot 73 in alignment with and adapted to accommodate the blades 64 and 65 when they are shifted inwardly. Block 72 is supported from bracket 74 by means of the screws 75 which extend through the block and engage and also support the plate 59.

Due to the fact that the cigarette packages are fed through the horizontal folding chute 41 by means of the reciprocating plunger 40, it will be appreciated that the packages have an intermittent motion. The knife blades 64 and 65 are caused to reciprocate and form the slits in the flaps of the wrapper while the package is temporarily in a stationary position. To accomplish this result, the arms 66 and 67 are connected to the driving mechanism of the machine, and are synchronized with the plunger 40. Thus it will be seen that the arm 67 is provided with a small bracket 76 supporting at the end thereof a follower in the form of a roller 77 which is held in engagement with cam 78 by means of spring 79 connected between the bracket and the frame of the machine. The cam 78 is preferably attached to the hub of sprocket 80 which engages the sprocket chain 31. Thus, when shaft 30 rotates, cam 78 engages follower 77 once during each revolution of the shaft causing arm 67 to oscillate. Oscillation of arm 67 causes a similar oscillation of arm 66 due to the interengagement between toothed segment 81, formed on one end of arm 66, and toothed segment 82, formed on the end of arm 67. Thus it will be seen that when the cam engages the follower, both arms together with their knife blades will be forced inwardly so as to engage and slit the edges of the flaps. When the cam no longer engages the follower, spring 79 will

return the arms to the position shown in Figs. 2 and 3.

The movement of arms 67 and 66 is coordinated with the reciprocation of plunger 40, and this can be readily accomplished because both the arms and the plunger are connected by driving mechanism to the primary drive shaft 21. The gearing and sprocket chain connections, shown in the illustrated embodiment, are of a one-to-one ratio so that there will be one revolution of shaft 30 for each reciprocation of plunger 40. Cam 78 is so arranged as to engage follower 71 when a cigarette package is in a stationary position with flaps projecting upwardly through the slots 57 and 58, and in engagement with the block 72. To accomplish this, cam 78 must engage its follower 71 after the dwell portion of cam 56 has released its engagement with follower 44.

After the slits or notches 71 have been formed in the flaps of the package, the package is again intermittently advanced through the folding chute with the result that flap 55 is folded downwardly, adhesive or a solvent is applied to the upper surface thereof, and thereafter flap 56 is folded downwardly on flap 55 and the adhesive is dried. The completed package is then discharged from the machine. Thereafter when it is desired to open the package, it will be seen that the removal of the wrapper, or of the upper portion thereof, is facilitated due to the fact that the tearing of the wrapper may be initiated from one or both of the slits 71.

From the foregoing description of the illustrated embodiment of my invention, it will be appreciated that I have provided a wrapping machine having an improved device for forming slits or notches in one or more of the edges of the wrapping material while it is being wrapped around the package. It should be appreciated, of course, that modifications may be made in the illustrated and described embodiment of my invention, such as incorporating the device for slitting the wrapping material in a different type of wrapping machine.

Each of the terms "slit" and "notch," as used herein and as used in the appended claims, is intended to have a broad generic meaning, designating any type of cut, tear or fracture formed in the sheet wrapping material, and the expressions are not intended to be limited to any specific form of cut, tear or fracture.

I claim:

1. A wrapping machine comprising means for wrapping sheet material partially around an article so as to provide two projecting flaps adjacent one end thereof, means for slitting each of the flaps so that they may be readily fractured, means for supporting said flaps while they are being slit, said means comprising a block having a slot position between said flaps and means for thereafter folding and securing the flaps downwardly against the article in superimposed relationship.

2. The combination with a wrapping machine

having a folding chute for wrapping sheet material partially around an article so as to leave two flaps projecting from one surface thereof and a second folding chute for folding the flaps against the article in superimposed relationship of a device for forming slits or notches in the projecting flaps before they are folded against the article to facilitate fracturing of the flaps, said device comprising a pair of cutter blades, a pair of arms supporting the blades and pivotally mounted adjacent the second folding chute so that the blades may be shifted into and out of engagement with the projecting flaps of an article positioned adjacent the beginning of the second folding chute, means for supporting said projecting flaps comprising a block, a slot in said block adapted to register in said blades and means for causing the reciprocal pivoting of the arms to cause the blades to engage and form slits in the projecting flaps of the article.

3. In combination with a wrapping machine which folds sheet material around an article and at one stage presents two projecting opposed sealing flaps at one end thereof, a device for slitting said flaps while in their projecting position, said device including arms mounted for movement, a cutter blade on each arm, means connected with one of said arms to operate it in timed accord with the folding operations, and coacting means on said arms to cause them to operate in unison to cause each blade to perform the slitting aforesaid, said coacting means consisting of toothed segments.

35 4. In combination with a wrapping machine which folds sheet material around an article and at one stage presents two projecting opposed sealing flaps at one end thereof, a device for slitting said flaps while in their projecting position, said device including arms mounted for movement, a cutter blade on each arm, means connected with one of said arms to operate it in timed accord with the folding operations, and coacting means on said arms to cause them to operate in unison to cause each blade to perform the slitting aforesaid, one of said blades disposed above the other to cup flaps respectively of different lengths.

50 5. In combination with a wrapping machine which folds sheet material around an article and at one stage presents two projecting opposed sealing flaps at one end thereof, a device for slitting said flaps while in their projecting position, said device including arms mounted for movement, a cutter blade on each arm, means connected with one of said arms to operate it in timed accord with the folding operations, and coacting means on said arms to cause them to operate in unison to cause each blade to perform the slitting aforesaid, one of said blades disposed above the other to cut flaps respectively of different length and a supporting block having a slot therein disposed between said flaps to support said flaps and to allow the passage of said blades.

ROBERT ROLAND BRIGHTWELL
